IRONING TABLE

John E. Kalgren, Minneapolis, Minn., assignor
to The J. R. Clark Co., Minneapolis, Minn.,
a corporation of Minnesota

Application May 7, 1930. Serial No. 450,427

5 Claims. (Cl. 68—10)

My present invention relates to ironing tables of the knock-down or folding leg type and especially to that type wherein the rear legs are caused to automatically spread when turned down or at right angles to the board and are drawn closer together when folded against the board. In the present board, the above objects are accomplished by a very simple and low cost construction which nevertheless, gives the board great rigidity when set up for use.

Generally stated, the invention consists of the novel devices, and combinations of devices hereinafter described and defined in the claims.

In the accompanying drawings which illustrate the invention, like characters indicate like parts throughout the several views.

Referring to the drawings:

Fig. 1 is a perspective showing the improved board set up for use;

20 Fig. 2 is a bottom plan view showing the board with its legs folded against the top board;

Figs. 3 to 9, inclusive, are fragmentary sections taken on the section lines marked with the corresponding numerals on Fig. 1, section line 5—5 being also shown on Fig. 9; and

Fig. 10 is a fragmentary view partly in side elevation but with some parts sectioned on the line 10—10 of Fig. 6.

The table top or ironing board proper is indicated by the numeral 11. Near its rear end this board is provided on its under side with rigidly secured hinge lugs preferably in the form of wooden cleats 12 which, as shown, converge slightly toward the upper free end of the board. Rear legs 13 are pivotally connected at their upper ends to the cleats 12 by rivets 14, these pivotal connections being made with sufficient play to permit the desired and considerable lateral spread and contraction of the rear legs. An oblique leg 15 which is a bifurcated structure made up of two wooden bars connected at their free floor-engaging ends by a rivet 16, is extended between the rear legs 13 and the bars thereof are pivotally connected to the hinge cleats 12 by rivets 17. These pivot-forming rivets 17 it will be noted are located considerably rearward of the pivot-forming rivets 14 and the bars of the oblique leg 15 at their pivoted ends are provided with obliquely cut projections 15^a that engage the bottom of the board 11 and limit the downward pivotal movement of said oblique leg.

The top brace made up of two wooden bars 18 is arranged to straddle the oblique leg 15 and the rear ends of its bars are pivotally connected

to intermediate portions of rear legs 14 by rivets 19. The free ends of the bars 18 of this top brace are tied together by a short tie-bar or strap 20 preferably of wood that is connected to the bars 18 by wood screws 21 or similar connections that will permit lateral spreading movements of the bars 18. At their intermediate portions, the bars of the top brace 18 are connected by a bridge bar 22 that at one end is connected to one of the bars 18 by a wood screw 23 or the like and at its other end is arranged to work loosely through a keeper strap or bracket 24 applied to the other bar of the said top brace. The free ends of the bars of the top brace 18 are detachably engageable with the bottom surface 70 of the board 11 and with a stop cleat or rib 25 applied to said board.

Leg braces 26 preferably in the form of metal straps connect the rear legs 13 to opposite bars of the oblique legs 13 to opposite bars of the 75 oblique legs 15. Said leg braces are thus applied in obliquely crossed arrangement and their lower ends are connected to the legs 13 by rivets 27 or the like while their upper ends are bent laterally and pivotally connected to the bars of the 80 oblique leg 15 by pivot-forming rivets 28 or the like.

By reference particularly to Fig. 1, it will be noted that the leg brace upper pivots 28 are offset from the rear leg pivots 14 and from the 85 oblique leg pivots 17. This arrangement is such that when the legs are moved pivotally toward folded positions against the board, the pivots 28 will be moved further away from the lower pivots 27 of the leg braces 26 and such relative movement causes the rear legs 13 to move more closely together on their pivots 14, so that when the parts are folded said legs 13 are well within the lateral dimensions of the top board 11. Conversely, when the legs are moved from 90 folded positions to operative position shown in Fig. 1, the pivots 28 will be moved toward and closer to the pivots 27 and the rear legs 13 will be caused to spread so as to give the proper lateral stability to the ironing board. 100 In the board illustrated in the drawings, the movement of the pivots 28 toward and from the pivots 27 is approximately one inch and the rear legs at their lower ends are given a lateral spread and contraction of nearly eleven inches, 105 but, of course, these relative dimensions and movements may be varied.

The lateral movements of the rear legs above described makes necessary also lateral movements of the bars of the top brace 18 and this, 110

as already noted, is permitted by the pivot-acting screws 21 and the keeper bracket 24. The arrangement of the parts is also such that when the free end of the top brace 18 is engaged with cleat 25, the short upper ends 15^a of the oblique leg 15 will be pressed against the bottom of the board and the bridge bar 22 will be pressed tightly against said oblique leg 15, thus putting all of the supporting elements under tension and affording a very rigid support for the board 11. From what has been said, it will be understood that the invention described is capable of modification as to details of construction and arrangement of parts herein disclosed and claimed.

15. What I claim is:

1. The combination with a board, of rear legs hinged thereto for forward, rearward and lateral movements, a bifurcated forwardly inclined oblique leg also pivoted to the board, a bifurcated top brace made up of two members and having the rear ends of its members pivoted to said rear legs and arranged to spread and move laterally therewith, the free end of said bifurcated top brace being directly engageable with the bottom of the board and removable therefrom, and transversely crossed rear leg braces attached to said rear legs at their lower ends and pivotally connected to the members of said bifurcated oblique leg at points offset from the pivot connections between the latter and said board, whereby said rear leg braces will cause said rear legs to spread laterally when said top brace is engaged with the board.

2. The structure defined in claim 1 in further combination with a bridge bar secured to one of the members of said bifurcated top brace and having endwise sliding engagement with the other member of said top brace, said bridge bar being engageable with said oblique leg when the board is set up for use.

3. The structure defined in claim 1 in further combination with a bridge bar secured to one

of the members of said bifurcated top brace and having endwise sliding engagement with the other member of said top brace, said bridge bar being engageable with said oblique leg when the board is set up for use, the members of said oblique leg having short upper ends engageable with the bottom of the board to limit the downward movement of said oblique leg.

4. The combination with an ironing board, of rear legs pivotally connected thereto for movements toward and from the board and for spreading movements, cooperating bifurcated board-supporting elements hingedly connected to the board for angular movements in respect thereto and in respect to the rear legs and having extended portions arranged to engage the board when the legs and cooperating board-supporting elements are set in board-supporting positions, and transversely crossed rear leg braces connected to said rear legs at one end and at their other ends pivotally connected to said cooperating bifurcated board-supporting elements at points offset from the pivotal connection between the latter and said board, whereby said rear legs will be spread when said legs and cooperating board-supporting elements are turned from the board to board-supporting positions.

5. The combination with an ironing board, of rear legs pivotally connected thereto for movements toward and from the board and for spreading movements, transversely crossed rear leg braces connected to said rear legs at one end, and cooperating board-supporting elements having angular movement in respect to said board and rear legs and having crank-acting connections to the other ends of said transversely crossed braces and arranged to spread said rear legs when said legs and cooperating board-supporting elements are turned to board supporting positions.

JOHN E. KALGREN.
